DISPENSING CARTON

Frank Spilski, Menasha, Wis., assignor to Marathon Paper Mills Company, Rothschild, Wis., a corporation of Wisconsin

Application March 19, 1936, Serial No. 69,712

2 Claims. (Cl. 206—58)

The present invention relates to dispensing cartons and particularly to a carton of the type for containing rolls of paper and the like, such for instance, as rolls of waxed paper from which the paper is dispensed in web form and torn in pieces of desired lengths against a cutter.

An object of the present invention is to provide a dispensing package adapted to hold a single roll of paper or other material so as to protect the same from dust and to permit the ready withdrawal of the paper web.

The invention further contemplates a package made from a single blank of material, which is scored and folded to provide a package of the requisite form and construction.

An important object of the invention is to provide a carton having a hinged front panel so as to permit ready grasping of the free edge of the paper web.

20 A further object of the invention is to provide a package which is economical to manufacture, easy to assemble, and efficient in use.

The above, other and further objects of the invention, will be apparent from the following description, the accompanying drawing and appended claims.

Embodiments of the invention are illustrated in the accompanying drawing and the views thereof are as follows:

30 Figure 1 is a perspective view of a box embodying the present invention.

Figure 2 is a transverse vertical section of the box illustrated in Figure 1.

Figure 3 is a fragmental perspective view of 35 one end of the box assembled except for the insertion of the end tabs.

Figure 4 is a fragmental perspective view of the box showing the hinge structure of the front panel.

40 Figure 5 is a plan view of the blank from which the carton is made.

The blank is cut and scored to provide a top wall 13, rear wall 12, the bottom wall 11, the front wall 14, a like panel 15, and a hinged panel 45 10, having affixed thereto a metal tear off strip 22.

The top wall 13 is provided with end flaps 17 which are scored to fold along lines 7 and cut along lines 9.

50 The bottom 11 is also provided with end flaps 16 which fold along scored lines 6.

The front panel 14 is provided with end tabs 18 which are scored to fold along lines 8 and these tabs have, in turn, tucks 19 which fold 55 along scored lines 30 with respect to the tabs

18. Tabs 17 and 18 are separated by cut lines 9. The front panel 14 is provided at its ends with slots 25 for receiving the hook portions 21 carried by the hinged panel 10.

The rear wall 12 has no end tabs.

5 The hinged panel 10 is scored at lines 31 to provide locking tongue portions 20 having hook portions 21. A tear-off blade 22 is secured to the hinged panel 10 so that its serrated edge will have the points of the serrations extending slightly beyond the edge of said panel 10. The tear-off blade may be fastened by any suitable means to the outside or inside of the panel 10.

The method of making a box from the blank illustrated in Figure 5 is as follows:

15 The blank is folded into box-like form by bending the panels 11, 12, 13, 14 and 15 along the score lines 1, 2, 3, 4 and 5, respectively. The dike panel 15 is folded so as to be positioned inside the box so formed and in contact with the inner surface of the bottom wall 11 as shown in Figure 3. By positioning panel 15 in this manner a dike or 20 passage is formed through which the sheet of waxed paper passes as illustrated in Figure 2. The weight of the roll 24 is applied on the panel 25 15 which in turn is exerted on the waxed paper web beneath it. This arrangement serves to apply a frictional force on the web as it is being withdrawn from the box thereby affording a smooth withdrawal of the web from the box. 30 The panel 15 also holds the end of the web after a piece of the web is severed on the tear-off blade 22 thereby preventing the end of the web from being withdrawn inside the box.

35 After the panels are folded up into box formation with the roll of paper inside the end tabs 16 and 17, respectively, of the top and bottom panels are folded in overlapping relation. The end tabs 18 of the front panel 14 are then folded over and the tucks 19 are inserted into locking arrangement. The hooked tongues 20 of the hinged panels 10 are then inserted through the slotted openings 25 as shown in Figures 3 and 4.

40 The hooked tongues 20 permit the panel 10, carrying the cutter blade 22, to hinge outwardly 45 along score line 1 for a limited distance as shown by the dotted line 10 in Figure 2. When the hooked portions or stops 21 abut the front wall 14 as shown in Figure 4 they act as stops to prevent further outward swinging of the hinged panel 10.

45 It is to be understood that the invention is not restricted to the specific means disclosed for limiting the outward swing of the hinged panel. Any other suitable means such as for example 50 55

pieces of flexible tape or wire attached to the box and the panel may be used if desired.

The hinged panel 10 provides means for securing ready access to the end 23 of the web after it is cut off along the cutter blade 22. By inserting the thumb between the front wall 14 and the hinged panel 10 it is possible to grasp the end of the web and then to draw out the desired length of web. The end of the web will not wind back inside the box as the web is held by the dike panel 15.

In using the carton it is simply held, say in the left hand, with the bottom 11 resting against the palm, the left thumb on the top 13 and the fingers 15 resting lightly on hinged panel 10. The thumb of the right hand is then inserted inside the hinged panel 10 so as to cause it to swing outwardly as shown in Figure 2 whereupon the end of the web 23 can be readily grasped and drawn 20 out to the required length and then cut off on the cutter blade.

The present carton is designed for use but once, and when the roll 24 has been exhausted the carton is thrown away. If desired, however, a new 25 roll can be readily replaced in the box.

The box made in accordance with this invention is strong and rigid enough for all purposes intended, pleasing in appearance, and one which lends itself very readily for use in connection 30 with rolled wax paper or other types of paper. The box is securely fastened together without the use of glue, paste, stickers, or like means thus making assembly rapid and economical.

It is to be understood that many changes may

be made in the proportion of parts and equivalents may be substituted or used without departing from the spirit and scope of the invention.

I claim:

1. A box for a supply of a rolled web formed 5 from a single blank of material, said blank being scored and foldable into box-like form with two panels in overlapping relation to provide a passage for the withdrawal of the web from the box, a wall adjacent said overlapped panels having slots at each end thereof, a hinged panel adjacent the overlapped panels to permit ready grasping of the end of the web after passing through said passage, said hinged panel being provided with folded hooked portions at the ends 10 thereof inserted in said slots for limiting the outward swinging thereof.

2. A box for dispensing a roll of web material comprising front, top, back and bottom walls, said top and bottom walls having end tabs, said front 20 wall having end tabs and tuck-in flaps and slots adjacent the end tabs, said tuck-in flaps being inserted between the back wall and the overlapped end tabs of the top and bottom walls, said front wall having a panel hinged thereto and positioned in overlapping relation with the bottom wall to provide a passage for withdrawal of the web, said bottom wall having an outwardly hinged panel overlapping the front wall, said hinged panel being provided with stop portions inserted 25 in said slots for engaging the front wall for limiting the outward swing of said hinged panel.

FRANK SPILSKI.
